WALL-MOUNTED SPHYGMOMANOMETER

George H. Jones, 4 Huron Ave., Massapequa, N.Y.

Filed Apr. 13, 1965, Ser. No. 84,761

Term of patent 14 years

(Cl. D83—12)

FIG. 1

FIG. 2

FIG. 3

FIG. 4

FIG. 5

FIG. 1 is a perspective view of the wall-mounted sphygmomanometer with its extension hose,

FIG. 2 is a side elevational view thereof, showing the swivel, wall-mounting bracket,

FIG. 3 is a rear elevational view thereof,

FIG. 4 is a top plan view thereof, and

FIG. 5 is a bottom plan view thereof. The characteristic features of my new design are shown in full in the drawings.

The hose inflation tube has been omitted in FIGS. 2-5 inclusive for convenience of illustration only.

I claim:

The ornamental design for a wall-mounted sphygmomanometer, as shown and described.
